UNITED STATES PATENT OFFICE.

JEDDY D. NIXON AND WALTER L. CHURCH, OF HOUSTON, TEXAS.

PACKER AND SETTING TOOL.

Application filed October 8, 1923. Serial No. 367,208.

To all whom it may concern:

Be it known that we, JEDDY D. NIXON and WALTER L. CHURCH, citizens of the United States, residing at Houston, in the county of Harris and State of Texas, have invented certain new and useful Improvements in a Packer and Setting Tool, of which the following is a specification.

This invention relates to new and useful improvements in a packer and setting tool.

One object of the invention is to provide a device of the character described embodying a packer for forming a water tight joint between the walls of a well bore, or casing in the well, and an inside pipe, or liner, set in said bore or casing, and embodies also a tool for setting or expanding said packer, and means for holding the packer in set, or expanded position.

Another object of the invention resides in the provision of a device of the character described through which the liner, or inside pipe, may be set in the bore, with its lower end securely seated in the bottom of the bore, and the packer then set so as to form a water tight joint between the upper end of the inside pipe and the casing, or walls of the bore, and the setting tool then released and withdrawn without unseating the inside pipe, or lifting it from its seat in the bottom of the bore.

A further feature of the invention resides in the provision of a setting tool by means of which the amount of expansion of the packer can be readily ascertained by the workmen at the ground surface.

A still further feature of the invention resides in the provision of a setting tool for packers to which a full string of pipe may be connected without reducing the working diameter of the bore, in case the packer should leak from beneath, or the casing should develop a leak above the packer.

With the above and other objects in view, the invention has particular relation to certain novel features of construction, operation and arrangement of parts an example

of which is given in this specification and illustrated in the accompanying drawings, wherein:

Figure 1 shows a side elevation of the complete device, shown partly in section.

Figure 2 shows a side view, partly in section, of the packer and means for securing the same in expanded position.

Figure 3 shows a transverse sectional view, taken on the line 3-3 of Figure 2.

Figure 4 shows a side elevation, partly in section, of the setting tool.

Figure 5 shows a transverse sectional view, taken on the line 5-5 of Figure 4; and,

Figure 6 shows a transverse sectional view taken on the line 6-6 of Figure 4.

Referring now more particularly to the drawings, wherein like numerals of reference designate similar parts in each of the figures, the numeral 1 designates the stem, or string of pipe which extends up to the ground surface, and through which the packer and setting tool are handled. A coupling 2 is screwed onto the lower end of this stem and a tubular reducing nipple 3 is threaded into the lower end of this coupling, the lower end of said nipple being rounded off, or tapered, as at 4. The numeral 5 designates a tubular mandrel whose upper end is attached to the lower end of the nipple, and whose lower end is flared, as at 6, and externally threaded. On the mandrel 5 there is a slidably sleeve 7, whose lower end is reduced forming a bushing 8, and both externally and internally threaded, and this lower end is vertically slotted, the slots 9 extending up partly through the sleeve 7 so to provide for the expansion and contraction of the bushing 8. The inside contour of the bushing 8 is similar to the contour of the flared lower end of the mandrel 5, but of somewhat smaller diameter, so as to be expanded thereby as hereinafter explained.

A tubular connecting nipple 10 is provided whose upper end is internally thread-

ed to receive the bushing 8. The lower end of the connecting nipple 10 has an annular seat 11, and beneath it is reduced and threaded to receive the coupling 12, by 5 means of which the liner, or inside pipe 13, is connected to the nipple 10. This liner extends to the bottom of the bore and rests on said bottom; and usually one or more joints of it are perforated, and formed into 10 a screen of any preferred construction, provided for the purpose of permitting the inflow of oil into the liner, but excluding sand and the like.

The threaded connections hereinbefore referred to are formed with right hand threads.

In order to wash out the well there is provided a wash pipe 14, whose upper end carries a collar 15, forming a head which 20 rests on the upper end of the reducing nipple 3, and sustains said wash pipe. This pipe extends down well towards the bottom of the bore so as to carry the water down past said screen in washing out the well.

25 There is a sleeve like packing element, as 15, around the nipple 10 and resting on the seat 11. This packing element may be formed of rubber, as shown, or of fabric, as burlap or the like, or of any other suitable expandable material.

Fitted over the upper end of the connecting nipple 10 and seated on the upper end of the packer 15, there is a collar 16 whose upper end has vertical slots 17 forming 35 the yieldable dogs 18, integral therewith. The upper end of the nipple 10 has external left hand buttress threads 19 and the dogs 18 are correspondingly internally threaded so as to mesh with said threads 19.

40 Threaded onto the collar 16, by right hand threads, and upstanding therefrom, there is the elongated tube 20 whose upper end is formed with a flared seat 21, for the purpose to be hereinafter explained.

45 The operation of the device is as follows:—The tool is assembled as shown in Figure 1 with the bushing 8 threaded down onto, and expanded by, the flared expander 6, and said bushing is also threaded into 50 the upper end of the nipple 10. The liner 13 is connected to said nipple and the complete device as thus assembled is connected, as explained, to the stem 1. When thus assembled, the coupling 2 will be spaced a few 55 inches above the seat 21, but a rigid connection will be provided between the stem and liner, and said liner may be forced down until its lower end forms a perfect seat on the bottom of the bore. The stem 60 1 may now be rotated to the right, and the expander 6 thus unscrewed from the bushing 8, and when so unscrewed will pass below said bushing, as shown in Figure 4, and the mandrel 5 will then slide down- 65 wardly through the sleeve 7. Above said

sleeve, the mandrel is provided with left hand buttress threads 22, and the upper end of said sleeve 7 has the vertical slots 23, staggered with relation to the slots 9, so as not to unnecessarily weaken the sleeve, 70 and forming integral yieldable dogs 24, having internal buttress threads to mesh with the threads 22. As the mandrel moves downwardly, the threads 22 being upwardly inclined, they will not engage with, but will 75 pass between said dogs 24, and beneath them, and the bushing 8, when released by the expander 6 will contract and free itself from engagement with the inside threads of the connecting nipple 10. The collar 2 will now 80 rest upon the seat 21, and through the tube 20 will force the collar 16 downwardly and expand the packing element 15 out against the casing, or walls of the bore and form a water tight joint therewith. The teeth 19 decline so that the dogs 18 during their 85 downward movement will readily expand and pass over said teeth but will engage therewith to prevent the upward movement of said collar, and they thus hold the packer 90 in expanded position when the stem is withdrawn. During this operation no upward pull is exerted on the liner, as in the case of packer setting tools now used, and there is no danger of unseating said liner from 95 the bottom of the bore, but on the other hand, a downward pressure is exerted against the liner, thereby seating it more securely in the bore.

The distance of the coupling 2 above the 100 seat 21, when the device is assembled, is known. When the expander 6 is released from the bushing 8, and the stem forced downwardly, as explained, the total downward movement can readily be observed by 105 the workmen, and this total distance, less the distance of the collar 2 above the seat 21, when assembled, will accurately indicate the amount of expansion of the packing element 10.

110 When the packer is set, the stem may be pulled upwardly carrying the mandrel 5 with it and as said mandrel moves upwardly, the teeth 22, will engage with the dogs 24, and carry the sleeve 7 along upwardly with the mandrel, and the bushing 8 being in contracted position will readily pass through the inside threads of the nipple 10 and the setting tool may thus be withdrawn with them, leaving the packer securely held in expanded position by the collar 16 and the dogs 18 thereof.

115 In some cases the packer will leak, permitting water to find its way from beneath up past the packer, and in the other case the casing above the packer will develop a leak; in such cases a full string of pipe must be connected to the liner and extended to the ground surface, as otherwise said water 120 would enter the top of the liner and mingle 125 with the oil. The stem 1 may be rotated to the right, and the expander 6 thus unscrewed from the bushing 8, and when so unscrewed will pass below said bushing, as shown in Figure 4, and the mandrel 5 will then slide down- 130 wardly through the sleeve 7. Above said

with the oil. In the case of packers now in common use this full string must have its lower end fitted within the packer structure, as said structure admits of the inflow 5 of water, and if said full string were connected onto the top of the structure, the leak into the top of the liner would not be shut off. If the string has its lower end fitted within the packer structure it 10 must necessarily be of smaller diameter than said structure and does not therefore provide adequate room for the pump rods, and makes it difficult to work through said string on account of said restrictions.

15 The tube 20 of the structure herein described makes the same water tight and in case it becomes necessary to employ a full string of pipe from the packer structure, to the surface of the ground, the ordinary 20 lead seal may be attached to the lower end of said string and the string then lowered until said seal seats on the seat 21, and forms a water tight joint therewith.

It is apparent that the string above the 25 packer may be of the same inside diameter as that of the liner beneath, thus providing sufficient space for the pump rods, or for working through said string when necessary.

We have shown and described what we 30 now consider the preferred form of the device, but it is apparent that structural variations may be made from the form shown without departing from the principle of the invention, and we hereby reserve the 35 right to make such modifications in structure as will not depart from the scope of the appended claims.

What we claim is:

1. In a setting tool, a mandrel, a flared 40 expander carried thereby, an expansible bushing adapted to fit over and be expanded by said expander, and a tubular support, for a packing element, into which the bushing is fitted.

45 2. In a setting tool, a mandrel, a flared externally threaded expander carried thereby, an expansible bushing internally threaded to receive said expander, said bushing being also externally threaded, a tubular packer 50 support internally threaded to receive said bushing.

55 3. In a setting tool, a mandrel, a flared externally threaded expander carried thereby, an expansible bushing mounted on the mandrel, and internally threaded to receive and be expanded by said expander said bushing being also externally threaded, a tubular packer support internally threaded, to receive said bushing, and to mesh there- 60 with when the bushing is in an expanded position.

65 4. In a setting tool, a mandrel, a flared externally threaded expander carried thereby, an expansible bushing internally threaded to receive said expander, said bush-

ing being also externally threaded, a tubular packer support, internally threaded to receive said bushing, a packing on said support means mounted on said support and adapted to operate against, and expand, said 70 packer, and interlocking means carried by said support and packer expanding means, respectively operating to hold the packer in expanded position.

5. In a setting tool, a mandrel, a flared 75 externally threaded expander carried thereby, an expansible bushing internally threaded to receive said expander, said bushing being also externally threaded, a tubular packer support, internally threaded to receive said bushing, a packing on said support means mounted on said support and adapted to operate against, and expand said 80 packer, and interlocking means carried by said support and packer expanding means, respectively, operating to hold the packer in expanded position, means mounted on said support and adapted to operate against, and expand said packer, and formed to interlock with the support to hold the packer 85 in expanded position.

6. A packer setting tool including a mandrel, a flared expander carried thereby, an expansible bushing mounted on the mandrel, and adapted to receive and be expanded 95 by said expander, a tubular packer support formed to receive and interlock with the bushing when the latter is expanded, a packer on said support a packer expanding element fitted around the support and provided to operate against and expand said packer, and interlocking means carried by the expanding element and packer support, respectively, through which the packer is 100 held in expanded position.

105 7. A packer setting tool including a mandrel, a flared externally threaded expander carried thereby, an expansible bushing mounted on the mandrel and internally threaded to receive and mesh with said expander, said bushing being also externally threaded, a packer support having internal threads to receive and mesh with said bushing when the same is expanded, a packer on said support a packer expanding means 110 around the support and adapted to operate against and expand the packer, engaging dogs carried by said packer expanding means and adapted to engage with said support, and hold the packer expanded.

115 8. A packer setting tool including a mandrel, an expander carried thereby, an expansible bushing movably mounted on the mandrel and formed to receive and be expanded by the expander, a packer support 120 formed to receive and interlock with the bushing when the latter is in expanded position, a packer on said support a collar surrounding said support, and adapted to operate against and expand said packer, yield- 125

able dogs carried by said collar and in engagement with said support.

9. A packer setting tool including a mandrel, an expander carried thereby, an expansible bushing movably mounted on the mandrel and formed to receive, and be expanded by, the expander, a packer support formed to receive and interlock with the bushing when the latter is in expanded position, a packer on said support a collar surrounding said support, and adapted to operate against and expand said packer, yieldable dogs carried by said collar and in engagement with said support, and a tubular extension upstanding from said collar whose upper end is formed with a seat.

10. A packer setting tool including a mandrel, a flared externally threaded expander carried thereby, an expansible bushing mounted on the mandrel and internally threaded to receive and mesh with said expander, said bushing being also externally threaded, a packer support having internal threads to receive and mesh with said bushing when the same is expanded, a packer on said support, a packer expanding means around the support and adapted to operate against and expand the packer, engaging dogs carried by said packer expanding means and adapted to engage with said support, and hold the packer expanded, an upstanding tubular member carried by said last mentioned means, and adapted to force the same against said packer to expand the same.

11. In a setting tool a mandrel, flared externally threaded expander carried thereby, an expansible bushing internally threaded to receive said expander, said bushing being also externally threaded, a tubular packer support, internally threaded to receive said bushing, a packer on said support, means mounted on said support and adapted to operate against, and expand, said packer, and interlocking means carried by said support and packer expanding means, respectively, operating to hold the packer in expanded position, an upstanding tubular member carried by the packer-expanding means and surrounding said interlocking means, and adapted to actuate the packer-expanding means against the packer.

12. In a setting tool, a mandrel, a flared externally threaded expander carried thereby, an expansible bushing internally threaded to receive said expander, said bushing being also externally threaded, a tubular packer support, internally threaded to receive said bushing, a packer on said support, means mounted on said support and adapted to operate against, and expand, said packer, and interlocking means carried by said support and packer expanding means, respectively, operating to hold the packer in expanded position, and an upstanding tubular member carried by the packer-ex-

panding means and surrounding said interlocking means, the upper end of said tubular member being formed with a flared seat.

13. A packer setting tool including a mandrel, a flared expander carried thereby, an expansible bushing movably mounted on the mandrel and formed to receive and be expanded by the expander, releasable interlocking means carried by the bushing and mandrel, respectively, through which the expander may be held in inactive position, relative to the bushing, a packer support formed to receive and interengage with, the bushing when the latter is expanded, a packer on said support a packer expander around said support, interengaging means carried by said packer-expander and said support.

14. A packer setting tool including a mandrel, a flared expander carried thereby, an expansible bushing movably mounted on the mandrel and formed to receive and be expanded by the expander, releasable interlocking means carried by the bushing and mandrel, respectively, through which the expander may be held in inactive position, relative to the bushing, a packer support formed to receive and interengage with, the bushing when the latter is expanded, a packer on said support a packer expander around said support, interengaging means carried by said packer-expander and said support, a stem to the lower end of which the mandrel is attached, and means sustained by said packer-expander and sustaining the weight of said stem.

15. A packer setting tool including a mandrel, a flared expander carried thereby, an expansible bushing movably mounted on the mandrel and formed to receive and be expanded by the expander, releasable interlocking means carried by the bushing and mandrel, respectively, through which the expander may be held in inactive position, relative to the bushing, a packer support formed to receive and interengage with the bushing when the latter is expanded, a packer on said support a packer expander around said support, interengaging means carried by said packer-expander and said support, a stem to which the mandrel is attached, and an upstanding tubular member carried by the packer-expander, and sustaining the load of said stem.

16. A packer setting tool including a mandrel, a flared outwardly threaded expander carried thereby, an expansible bushing movably mounted on the mandrel and internally threaded to receive and mesh with the expander, said bushing being also externally threaded, a packer support internally threaded to receive and mesh with the bushing when the latter is expanded, a packer on said support a packer expander adapted to operate against and expand the

5 packer, interlocking means carried by the packer expander and said support, respectively, and operating to hold the packer expanded, a stem to which the mandrel is attached, an upstanding tubular member carried by the packer-expander and sustaining the weight of the stem.

10 6 17. In combination, a tubular support having internal threads, an expansible packing element on said support, a packing expander sustained by said packing element, interlocking means carried by said support and expander, respectively, an upstanding tubular member attached to said expander and adapted to actuate the same against said packing element, a mandrel within said tubular member, a flared externally threaded expander carried by the mandrel, an expansible internally threaded bushing formed 70
15 to receive and mesh with said flared expander, said bushing being also externally threaded to mesh with the threads of said support when said bushing is expanded.

20 18. In combination a tubular support having internal threads, an expansible packing element on said support, a packing expander sustained by said packing element, interlocking means carried by said support and expander, respectively, an upstanding tubular member attached to said expander, a mandrel within said tubular member, a flared externally threaded expander carried by the mandrel, an expansible internally threaded bushing formed to receive and 80
25 mesh with said flared expander, said bushing being also externally threaded to mesh with the threads of said support when said bushing is expanded, a stem to which said mandrel is attached, an external shoulder on 90
30 the stem adapted to rest on said tubular member.

35 19. In combination, a tubular support having internal threads, an expansible packing element on said support, a collar sustained by said packing element, yieldable dogs carried by said collar, and adapted to engage with said support, a mandrel, a flared externally threaded expander carried by the mandrel, a sleeve whose lower end is 95
40 formed into an internally threaded, expansible bushing provided to receive said flared expander and be expanded thereby, dogs carried by said sleeve, means on the mandrel provided to engage with said dogs of said sleeve to hold said bushing in inactive position relative to said flared expander, said means being releasable from said dogs, said bushing being also externally threaded and adapted to enter and intermesh with the threads of said support, a tubular member supported by and upstanding from said collar, and whose upper end is formed with a flared seat.

45 20. In combination, a tubular support having internal threads, an expansible packing element on said support, a collar sustained by said packing element, yieldable dogs carried by said collar, and adapted to 100
50 engage with said support, a mandrel, a flared externally threaded expander carried by the mandrel, a sleeve whose lower end is formed into an internally threaded, expansible bushing provided to receive said flared expander and be expanded thereby, dogs carried by said sleeve, means on the mandrel provided to engage with said dogs of said sleeve to hold said bushing in inactive position relative to said flared expander, said means being releasable from said dogs, said bushing being also externally threaded and adapted to enter and intermesh with the threads of said support, a tubular member supported by and upstanding from said collar, and whose upper end is formed with a flared seat.

55 21. In combination a tubular support having internal threads, an expansible packing element on said support, a collar sustained by said packing element, yieldable dogs carried by said collar, and adapted to engage with said support, a mandrel, a flared externally threaded expander carried by the mandrel, a sleeve whose lower end is formed into an internally threaded, expansible bushing provided to receive said flared expander and be expanded thereby, dogs carried by said sleeve, means on the mandrel provided to engage with said dogs of said sleeve to hold said bushing in inactive position relative to said flared expander, said means being releasable from said dogs, said bushing being also externally threaded and adapted to enter and intermesh with the threads of said support, a tubular member supported by and upstanding from said collar, and whose upper end is formed with a flared seat.

60 22. In combination a tubular support having internal threads, an expansible packing element on said support, a collar sustained by said packing element, yieldable dogs carried by said collar, and adapted to engage with said support, a mandrel, a flared externally threaded expander carried by the mandrel, a sleeve whose lower end is formed into an internally threaded, expansible bushing provided to receive said flared expander and be expanded thereby, dogs carried by said sleeve, means on the mandrel provided to engage with said dogs of said sleeve to hold said bushing in inactive position relative to said flared expander, said means being releasable from said dogs, said bushing being also externally threaded and adapted to enter and intermesh with the threads of said support, a tubular member supported by and upstanding from said collar, and whose upper end is formed with a flared seat.

65 23. A setting tool including a mandrel, a

70 75 80 85 90 95 100 105 110 115 120 125
engaging with said support, a mandrel, a flared externally threaded expander carried by the mandrel, a sleeve whose lower end is formed into an internally threaded, expansible bushing provided to receive said flared expander and be expanded thereby, dogs carried by said sleeve, means on the mandrel provided to engage with said dogs of said sleeve to hold said bushing in inactive position relative to said flared expander, said means being releasable from said dogs, said bushing being also externally threaded and adapted to enter and intermesh with the threads of said support, and a tubular member supported by and upstanding from said collar, adapted to actuate the packer expanding means against the packer.

90 95 100 105 110 115 120 125
24. In combination a tubular support having internal threads, an expansible packing element on said support, a collar sustained by said packing element, yieldable dogs carried by said collar, and adapted to engage with said support, a mandrel, a flared externally threaded expander carried by the mandrel, a sleeve whose lower end is formed into an internally threaded, expansible bushing provided to receive said flared expander and be expanded thereby, dogs carried by said sleeve, means on the mandrel provided to engage with said dogs, of said sleeve to hold said bushing in inactive position relative to said flared expander, said means being releasable from said dogs, said bushing being also externally threaded and adapted to enter and intermesh with the threads of said support, a tubular member supported by and upstanding from said collar, and whose upper end is formed with a flared seat.

120 125
25. A setting tool including a mandrel, a flared seat, a stem to the lower end of which the mandrel is attached, said stem having an external shoulder adapted to rest on said seat.

26. A setting tool including a mandrel, a

- flared expander carried thereby, an expandable bushing adapted to fit over and be expanded by said expander and a tubular member into which said bushing is fitted.
- 5 24. A setting tool including a tubular member, a mandrel, a flared expander carried by the mandrel, a sleeve whose lower end is formed into an expandible bushing provided to receive said expander and to be expanded thereby, interengaging means carried by said sleeve and mandrel respectively; and adapted to hold said bushing in inactive position relative to the expander, said interlocking means being releasable and said bushing being adapted to enter said tubular support, said support and bushing being formed to interlock.
- 10 25. In a device of the character described a tubular support, whose upper end has internal right hand threads, adapted to receive a setting tool, an expandible packing element on said support, a collar on said support abutting against said packing element, yieldable dogs associated with said collar and adapted to engage the support and a tubular member associated with the collar through which the collar may be actuated to expand the packing, the upper end of the tubular member having a flared seat.
- 15 26. In a device of the character described a tubular support, an expandible packing element on said support, a tubular upstanding member sustained by the packing element and through which said packing element may be expanded, and interlocking means through which said tubular member may be locked, in relation to the support to hold the packing element in expanded position.
- 20 27. A setting tool including a mandrel,
- whose lower end is flared and externally threaded, a bushing having an internally threaded section adapted to receive said flared end of the mandrel, and releasable interlocking means carried by said mandrel and bushing respectively.
- 25 28. A setting tool including a mandrel having a flared portion, a bushing having an internal flared section adapted to receive said flared portion of the mandrel, said bushing also having external threads, to receive a tubular packer support and releasable interlocking means carried by said mandrel and bushing respectively.
- 30 29. A setting tool including a mandrel having a threaded flared portion, a bushing on the mandrel having an internally threaded section adapted to receive the flared portion of the mandrel, said bushing also having external threads, to receive a packer support, and releasable interlocking means carried by the mandrel and bushing respectively.
- 35 30. A setting tool including a mandrel having a flared portion, an expandible bushing on the mandrel having an internal flared section adapted to receive the flared portion of the mandrel to expand the bushing, said bushing also having external threads to receive a packer support, and releasable interlocking means carried by the mandrel and bushing respectively.
- 40 In testimony whereof we have signed our names to this specification in the presence of two subscribing witnesses.
